UNITED STATES PATENT OFFICE.

FRITZ ECKERT, OF WETZLAR, GERMANY.

HOLLOW WALL.

Application filed September 3, 1921. Serial No. 498,533.

(GRANTED UNDER THE PROVISIONS OF THE ACT OF MARCH 3, 1921, 41 STAT. L., 1313.)

To all whom it may concern:

Be it known that I, FRITZ ECKERT, a citizen of the German Republic, residing at Wetzlar, Germany, have invented certain new and useful Improvements in Hollow Walls (for which I have filed applications in Germany, June 14, 1919, Patent No. 339,943; Belgium, July 14, 1921, Patent No. 237,959; Denmark, July 12, 1921; England, 10 July 13, 1921; France, July 12, 1921, Patent No. 538,185; Holland, July 19, 1921; Italy, July 19, 1921; Norway, July 14, 1921; Austria, July 7, 1921; Spain, July 14, 1921, Patent No. 78,802; Sweden, July 8, 15 1921; Switzerland, July 6, 1921; Czechoslovakia, May 27, 1921; Poland, September 16, 1921), of which the following is a specification.

For attaining a saving in the cost of building, it has been proposed to erect hollow walls of standard bricks in which these are arranged as stretchers on edge, and transverse connecting members or headers also on edge are also used as bonding, being arranged one above another in all the courses so that vertical through passages or shafts are formed. With such a method of construction the mortar falling into the shafts which extend the height of the story 25 cannot be recovered, or can only be got out with difficulty. Moreover, in shafts of full story height an air circulation is produced which is not conducive to the desired protection from heat or cold.

In another method of construction the courses of stretchers laid on edge, and of headers, recur at regular intervals and in lieu of standard bricks specially dimensioned bricks are used, while upright bonding 30 bricks are completely dispensed with. This arrangement necessitates the use of a considerable amount of bricks and mortar.

The hollow wall of standard bricks forming the subject of the present invention is 35 intended to avoid the disadvantages mentioned. As compared with the first mentioned method of construction it differs in this that the bonding bricks are not located above one another throughout the courses so that the formation of vertical shafts is 40 avoided and a division of the whole of the hollow space into horizontal passages is

brought about by full courses of bonding 55 bricks in the form of headers laid flat. As the result, the mortar dropping into the hollow spaces can easily be recovered, and this is a matter of importance for cheap construction and moreover, better protection 60 from heat and cold is obtained by reason of the small movement of air.

Compared with the second method of construction referred to there is obtained by the present construction of hollow wall, a saving of bricks and mortar since the 65 courses of bonding bricks laid flat need only occur at considerable intervals, sufficient strength being secured by placing occasional bonding bricks at suitable intervals in the wall.

In the accompanying drawing is shown 70 the corner of a hollow wall:

Fig. 1 being a perspective view showing a wall one brick thick.

Fig. 2 shows the bonding of the hollow 75 wall in plan, while

Fig. 3 is an illustration corresponding to Fig. 2 of a hollow wall one and a half 80 bricks thick.

As shown the standard bricks placed on edge in the inner and outer walls a' and a^2 of the hollow wall are bonded at certain lateral distance apart by bonding bricks d . At certain vertical distances apart is laid a complete course of flat headers f which has for its object to anchor the inner and outer 85 walls together and to subdivide the insulating air space of the whole story. Several courses of such flat bonding bricks may be provided at changes of thickness to support the beams, thus saving corbels. The quoins 90 g , g' as also the door and window reveals, are constructed as shown in the drawings, in solid brickwork. For the sake of clearness the bonding bricks d and courses of flat headers f are indicated by hatched lines. 95

In the hollow wall a' , a^2 one brick thick only one hollow space is provided but in the walls a' , a^2 , a^3 , one and a half bricks thick, two hollow spaces are provided. The bonding bricks d may be disposed as shown 100 in Fig. 3 or in any other similar manner.

I claim:

A hollow wall of standard bricks wherein there are interposed in the courses formed

of stretchers separate bonding bricks in such a manner that the vertical course is interrupted repeatedly and the vertical shaft is shut off at these parts and several complete courses of headers laid flat dividing the whole of the hollow space into horizontal passages.

In testimony whereof I affix my signature in presence of two witnesses.

FRITZ ECKERT.

Witnesses:

BERNHARD KAISER,

CARL FRIEDRICH ERSZUG.
